Attorneys

UNITED STATES PATENT OFFICE.

SAM HERSCHE, OF CLEVELAND, OHIO.

HUMIDIFIER.

Original application filed January 23, 1925, Serial No. 4,334. Divided and this application filed October 15, 1925. Serial No. 62,525.

It is customary to provide in hot air furnaces air-humidifying means comprising a receptacle into which water may be introduced from the exterior of the furnace and from which this water may evaporate into the air current. As these receptacles are usually constructed at the present time, however, there is no way to close the opening through which the water evaporates into the air current and accordingly water being poured into the receptacle very often splashes over in appreciable quantity into the interior of the furnace where it produces obvious detrimental results. The principal object of my invention is to provide humidifying means of this type free from this objection. In the drawings accompanying this specification and forming a part of this application I have shown, for purposes of illustration, one form which my invention may assume. In these drawings:

Figure 1 is a fragmentary side elevation of a furnace embodying this illustrative form,

Figure 2 is a fragmentary section on the line 2—2 of Figure 1.

Figure 3 is a fragmentary section on the line 3—3 of Figure 2, while

Figures 4 and 5 are fragmentary sections similar to Figure 3 showing optional methods of supporting the cover on the receptacle.

The present application is a division of my copending application Serial Number 4,334 filed January 23, 1925.

The embodiment of my invention disclosed herein comprises a receptacle 11 supported by the base plate 12 of the furnace 13 in position extending through and closing an aperture 14 in the furnace wall 15, and provided with an open top 16 divided by the furnace wall 15 into an outer opening 17 through which water may be inserted into the receptacle 11 and an inner opening 18 through which water may evaporate into the air current within the furnace wall 15. Mounted upon this receptacle 11, by means of trunnions 19 pivotally supported in arcuate projections 20 on the side walls 21 of the receptacle 11, is a cover 22 comprising an outer portion 23 arranged to overlie and close the outer opening 17 and an inner portion 24 arranged to overlie and close the inner opening 18 but disposed at an angle to the outer portion 23 so that when the outer

portion 23 is in position closing the outer opening 17 the inner portion 24 is raised from the inner opening 18 as shown in full lines in Figure 2, and when the inner portion 24 is in position closing the inner opening 18 the outer portion 23 is raised from the outer opening 17 as shown in dotted lines in Figure 2.

In Figures 4 and 5 I have shown optional forms of supporting the cover from the receptacle, the form in Figure 4 comprising trunnions 25 carried by the cover 26 and pivotally supported in arcuate projections 27 extending exteriorly of the side walls 28 of the receptacle 29, and the form in Figure 5 comprising trunnions 30 carried by the cover 31 and pivotally supported in recesses 32 formed directly on the side walls 33 of the receptacle 34.

It will be apparent that the embodiment of my invention herein shown provides a closure for the inner receptacle opening and therefore provides means to prevent water splashing into the interior of the furnace. It will also be apparent that in the form of my invention herein illustrated this cover is connected to and correlated with the cover closing the outer opening in such manner that movement of the outer cover to expose the outer opening automatically closes the inner opening. It will therefore be obvious that the form of my invention herein illustrated accomplishes the principal object of my invention.

On the other hand, it will at the same time be obvious by those skilled in the art that the particular embodiment of my invention herein shown and described may be variously changed and modified without departing from the spirit of my invention or sacrificing the advantages thereof. It will therefore be understood that this disclosure is illustrative only and that my invention is not limited thereto.

I claim:

1. Means for humidifying the air of a hot air furnace, comprising a receptacle and a unitary cover for said receptacle comprising two leaves meeting along a common edge, pivoted on an axis generally parallel to that edge, and disposed at an angle to each other so that either is in closed position when the other is in open position, one of said leaves being adapted to close that part of the receptacle lying within the fur-

nace wall when said receptacle is in operative position and the other of said leaves being adapted to close that part of the receptacle lying outside the furnace wall when 5 said receptacle is in such position.

2. Means for humidifying the air of a hot air furnace, comprising an open top receptacle and a unitary cover for said receptacle comprising two leaves meeting along 10 a common edge, pivoted on an axis generally parallel to that edge and to the open top of said receptacle, and disposed at an angle to each other so that either is in closed position when the other is in open position, 15 one of said leaves being adapted to close that part of the open top of said receptacle lying within the furnace wall when said receptacle is in operative position, and the other of said leaves being adapted to close that 20 part of the open top of said receptacle lying outside the furnace wall when said receptacle is in such position.

3. Means for humidifying the air of a hot air furnace, comprising a receptacle and a 25 unitary cover comprising two leaves meeting along a common edge, pivoted on an axis generally parallel to that edge and lying substantially in said furnace wall when said receptacle is in operative position, and 30 disposed at an angle to each other so that

either is in closed position when the other is in open position, one of said leaves being adapted to close that part of the receptacle lying within the furnace wall when said receptacle is in operative position and the 35 other of said leaves being adapted to close that part of the receptacle lying outside the furnace wall when said receptacle is in such position.

4. Means for humidifying the air of a 40 hot air furnace, comprising an open top receptacle and a unitary cover comprising two leaves meeting along a common edge, pivoted on an axis generally parallel to that edge and to the top of said receptacle and 45 lying substantially in said furnace wall when said receptacle is in operative position, and disposed at an angle to each other so that either is closed when the other is in open position, one of said leaves being adapted 50 to close that part of the open top of said receptacle lying within the furnace wall when said receptacle is in operative position, and the other of said leaves being adapted to close that part of the open top of said 55 receptacle lying outside the furnace wall when said receptacle is in such position.

In testimony whereof I hereunto affix my signature.

SAM HERSCHE
